SCREEN DOOR BRACE

Guy A. Wellman, Geneva, Ohio, assignor to The Champion Hardware Company, Geneva, Ohio, a corporation of Ohio

Application February 24, 1934, Serial No. 712,767

9 Claims. (Cl. 20—38)

This invention has to do with braces and, more particularly, with braces for the frames of door screens, window screens or the like.

An object of the invention is to provide an improved brace, of the type mentioned, which is of simplified and economical construction, which can be easily and quickly applied to the screen frame without the need of special tools or equipment, and which is of such form that the desired degree of frame correction can be readily obtained either at the time of initial installation of the brace, or by adjustment from time to time as conditions may require.

Another object of the invention is to provide an improved brace, of the type mentioned, embodying two parts adapted to be connected respectively to different portions of the screen frame, and wherein an adjustable connection between the parts for varying the length of the brace includes a plurality of locking elements arranged on one of the parts so as to extend as a series in angular relation with respect to the frame, and locking means rigid with the other part for selective cooperation with the locking elements of the series.

A further object of this invention is to provide an improved brace, of the type mentioned, comprising an elongated member connected to one portion of the frame and having a locking part integral therewith, and a bracket member secured to another portion of the frame and having an angularly disposed series of locking teeth thereon adapted to be selectively engaged by the locking part of the elongated member.

It is also an object of this invention to provide an improved and simplified screen door brace comprising an elongated member having pivotal connection with one portion of the screen door frame, and a second member secured to another portion of the screen door frame and having a hook portion provided with an angularly disposed series of teeth, the elongated member having an opening therein to adjustably receive the toothed hook portion.

Other objects and advantages of this invention will be apparent from the following description when taken in conjunction with the accompanying sheet of drawing, wherein

Fig. 1 is an elevational view showing a portion of a screen to which a brace embodying my invention has been applied.

Fig. 2 is a similar elevational view of another screen and showing another brace embodying my invention.

Fig. 3 is a detached elevational view of the

brace of Fig. 1, but showing the same on a somewhat larger scale.

Fig. 4 is a similar elevational view of the brace shown in Fig. 2.

Fig. 5 is a perspective view of the bracket member of the brace illustrated in Figs. 1 and 3.

Fig. 6 is a perspective view showing the locking portion of the elongated member of the brace shown in Fig. 1.

Fig. 7 is a perspective view showing the bracket member of the brace illustrated in Fig. 2, and

Fig. 8 is a perspective view of the locking portion which cooperates with the bracket of Fig. 7.

Detailed reference will presently be made to the accompanying drawing wherein I have illustrated an improved and simplified form of brace to be used on the frames of door screens, window screens, or the like for maintaining or correcting the shape of such frames. Before proceeding with such detailed description, it will be understood of course that the invention may be embodied in various other arrangements of parts than herein illustrated, and that the brace of my invention may be applied to various kinds of frames or apparatus in addition to the screen frames illustrated in the drawing.

In Fig. 1 of the drawing I have shown a portion of a screen of conventional form, such as might be used as a screen door or a window screen, and have shown my improved brace applied to this screen for the purpose of adjusting and maintaining the shape of the frame of the screen so as to eliminate sag and enable the screen to be more accurately accommodated to the door or window frame with which it is to be used. The particular screen shown in this instance is provided with a marginal frame which includes side rails or stiles 10, 11 and two or more transverse rails 12. A sheet or web 13 of screen material, such as wire screening, may be attached to the frame in the usual manner. My improved brace 14 is preferably applied to the screen at one of the corners thereof so that when properly adjusted it will tend to lift the opposite corner of the screen to correct and maintain the shape of the frame and thereby eliminate undesirable sag.

This brace, as shown in the drawing, is of very simple construction and comprises a bracket member 15, and an elongated member 16. These members are connected, respectively, to different portions of the screen frame, for example the bracket member may be connected to the side rail 10 and the elongated member may be connected to the end rail 12. As will be presently explained, the members 15 and 16 are provided

with cooperating parts forming an adjustable connection for varying the length of the brace to thereby eliminate the undesirable sag mentioned above.

5 The bracket member 15 may be of any suitable construction, for example it may be a cast-metal part, and is preferably provided with a base portion 17 which can be conveniently attached to the rail 10 by suitable screws 18. The member 15 10 is also provided with a hook portion 19, which extends in angular relation to the base portion 17 and the rail 10, and has a plurality of locking elements thereon. These locking elements are preferably in the form of serrations or teeth 20 which are arranged to extend in a series along the angularly disposed hook portion.

15 The elongated member 16 may likewise be of any suitable construction, for example, it may be a metallic member of channel-like cross section. 20 This elongated member is connected to another portion of the frame, such as the end rail 12 and, if desired, this connection may be made as a pivotal connection to permit swinging of the elongated member. For this purpose a suitable connecting clip or bracket 21 may be used and is pivoted to the elongated member and attached to the end rail 12 by suitable screws.

25 The opposite end of the elongated member 16 is provided with a locking part 22 which is rigid with, and preferably also integral with, the elongated member and which cooperates with the angularly disposed series of locking elements 20. In this instance the locking part 22 is shown as being provided with an elongated opening 23 therethrough which receives the hook portion 19 30 of the bracket member 15. If desired, the edge 24 of the opening 23 may be made of V-shape so that it will readily engage in the grooves between the adjacent locking teeth of the series. 35 From the arrangement just described it will be seen that the hook part 19, which supports the series of teeth and extends through the opening 23, also serves as a guide for the locking part 22 of the elongated member so that this part may be 40 readily shifted along the series of locking teeth for varying the length of the brace.

45 The free end of the hook portion 19 may be provided with a stop 25 to prevent the locking part 22 from becoming detached from the bracket member after the parts have once been assembled and applied to the screen frame. This stop may be formed integral with the hook portion of the bracket member and may be elongated in the transverse direction so that the elongated opening 23 50 of the member 16 will accommodate the stop only when the member 16 extends transversely of the hook portion.

55 It might well be explained at this point that the angular relation of the series of locking teeth 20 to the rail 10 is such that the straight line distance from the pivot point of the clip 21 to the tooth at the outer end of the series is shorter than the straight line distance from the pivot point to the innermost tooth of the series. In other 60 words the angular arrangement of the series of teeth is such that as the member 16 is swung so as to move the locking part 22 along the hook part 19 toward the rail 10, there will be a progressive shortening of the brace which causes a 65 lifting force to be transmitted therethrough.

70 In applying the brace to the frame of a screen door or the like, the parts 15 and 16 are arranged in approximately the relative positions shown in Fig. 1 but with the locking part 22 immediately adjacent to the stop 25, and after being attached

75 to the frame the locking part 22 of the elongated member is adjusted to a position along the series of teeth which will cause the opposite corner of the frame to be lifted an amount sufficient to eliminate the sag. In making this adjustment pressure may be applied to the screen frame at diagonally opposite corners and the locking part of the elongated member 16 may be shifted along the series of locking teeth toward the base portion 17 of the bracket while such pressure is being 10 maintained. Adjustment of the locking part in this direction shortens the brace, as explained above, and the sagging corner of the frame is thereby lifted and retained in the desired position of adjustment.

15 In Figs. 2, 7 and 8 of the drawing I have shown the principle of my invention embodied in another brace which is also of very simple construction. As shown in Fig. 2, this latter form of brace may be applied to the corner of a screen frame 20 having side rails 28 and 29 and transverse rails 30, and when thus applied the brace tends to lift the outer rail 29 to correct undesirable sagging of the frame. The brace of Fig. 2 comprises an elongated member 31 having one end thereof connected to the side rail 28, as by means of a suitable bracket or clip 32 and pivotal connection 33, and a bracket 34 which may be connected to the transverse rail 30. The bracket 34 is provided with an angularly disposed series of locking elements, 25 preferably in the form of teeth or serrations 35. The elongated member 31 is provided, preferably at its free end, with an integral rigid locking part 36 which is shiftable along the series of locking teeth for varying the length of the brace. 30

35 The bracket 34 may be made from sheet metal by bending or forming the same to suitable shape such as the shape illustrated in Fig. 7. The serrations or teeth 35 may be formed on the arm 37 of this bracket and may be arranged in two 40 rows disposed on opposite sides of a slot 38 extending through the bracket. The locking part 36 of the elongated member may be provided with a substantially T-like projection 39 which extends through the slot 38 of the bracket. The 45 locking part 36 may also be provided with a V-shaped edge 40 for engagement in the grooves between the adjacent teeth of the series carried by the bracket 34. The T-like projection 39 serves to retain the locking part of the elongated 50 member in cooperating relation with the bracket and also serves as a guiding means for this part of the elongated member.

55 When adjustment of the screen frame is to be made, the members 31 and 34 are applied, respectively, to the rails 28 and 30 of the screen frame and, by applying pressure to diagonal corners of the screen frame, the shape of the frame may be changed sufficiently to eliminate the undesirable sag and, while such pressure is being 60 maintained, the locking part 36 is shifted along the series of teeth 35 in a direction toward the apex of the bracket 34. Because of the angular position of the series of teeth, the shifting of the locking part 36 in the direction mentioned 65 causes the brace to be lengthened which lifts the rail 29 and takes up the sag in the frame. When the locking part 36 has been shifted sufficiently to take up the sag in the screen frame, it will be retained in the desired position of adjustment by the locking teeth, and the screen frame will then be retained in the desired shape by the brace.

70 In the drawing I have shown the frame braces of Figs. 1 and 2 as being connected to the inner 75

edges of the rails of the screen frame, but it will be understood, of course, that the same braces could also be arranged to be connected to the flat outer faces of the rails of the frames, if that were found to be desirable.

It will be noted that in the brace of Fig. 1 and also in the brace of Fig. 2, the series of locking elements and the elongated member are arranged so that the axis of the elongated member extends approximately at right angles to the line of locking elements. With this relation of the parts, an efficient locking connection is obtained which is not likely to be jarred out of adjustment, and the force transmitted through the brace is most effective at this angle for assisting in retaining the parts in locking engagement with each other. It will also be noted, that in both of the devices herein disclosed the angular relation of the series of teeth tends to cause the V-edge of the locking part to be wedged down into the groove between adjacent teeth and since the wedging action is increased by any disengaging movement of the V-edge, the parts are not likely to be jarred out of adjustment.

From the foregoing description and accompanying drawing it will now be readily seen that I have provided a form of screen frame brace which is made up of very few parts and which is of extremely simple and economical construction. It will be seen furthermore that my improved brace can be readily applied to the screen frame by persons who are not skilled mechanics and will serve efficiently to take up undesirable sag in the screen frame and retain the same in the desired adjusted condition. It will be noted further, from the drawing and the foregoing description, that the locking elements provided on one member of the brace are arranged in a series which extends in angular relation with respect to the screen frame, and that the locking part of the other member which cooperates with such series of locking elements, is integral and rigid with such other part. With this arrangement I find that the screen brace of my invention can be constructed to comprise only two parts, thus eliminating or reducing in number the various movable-part arrangements provided in the adjustable screen frame braces heretofore proposed.

Having thus described my invention, I claim:

1. A screen-frame brace comprising a hook member for connection with a portion of the frame, said hook member having a portion thereof provided with a series of teeth arranged to extend in inclined angular relation to said frame portion, and means for connection with another portion of the frame and provided with a locking part having an opening adapted to receive the toothed portion of said hook member, said locking part being shiftable along said inclined series to vary the length of the brace.

2. A screen-frame brace comprising a bracket adapted for attachment to a portion of the frame and having a slotted portion extending in inclined relation to such frame portion, said slotted portion having a series of locking elements thereon, and a member adapted for attachment with another portion of the frame and having parts rigid therewith including a part adapted to extend into the slot of said inclined bracket portion and a part for selective engagement with the locking elements of said series.

3. A screen-frame brace comprising a bracket adapted for attachment to a portion of the frame

and having a slotted portion extending outwardly in inclined relation to such frame portion, said slotted portion having a series of teeth thereon, and an elongated member adapted to be connected to another portion of the frame and having at one end thereof means for selective locking engagement with said teeth including a T-like part extending through the slot of the toothed bracket portion, said rigid parts being shiftable along said series to vary the length of the brace.

4. A screen-frame brace comprising two parts adapted to be connected respectively with different portions of the frame and having an adjustable connection therebetween for varying the length of the brace, said connection comprising an arm on one of said parts projecting from the frame portion to which such one part is connected and extending in inclined angular relation to the direction in which such frame portion extends, locking elements extending in an elongated series along such inclined arm, and means rigid with the other of said parts for selective engagement with the locking elements of said series, said rigid means being shiftable along the inclined series of elements whereby the angularity of the latter causes the length of the brace to be varied.

5. A brace for a frame having connected rail members, comprising an elongated part having one end thereof pivotally attached to one of said rail members and having a locking part at its other end, and a bracket attached to another of said rail members and having an arm projecting from the rail and extending in inclined angular relation to the direction in which such rail extends, said arm having a plurality of locking elements thereon adapted to be selectively engaged by said locking part and arranged to extend in an elongated series along such inclined arm and transversely to the axis of said elongated part whereby shifting of said locking part along the series of elements varies the length of the brace.

6. A screen-frame brace comprising an elongated member having one end thereof adapted for connection with one portion of the frame and having an integral locking part at its other end, and a member adapted for attachment with another portion of the frame and having a hook part arranged to extend in inclined angular relation to the direction in which such other frame portion extends, said hook part having locking elements thereon adapted to be selectively engaged by said locking part and arranged to extend in an elongated series along such inclined hook part whereby shifting of said locking part along said series varies the length of the brace.

7. A screen-frame brace comprising a member adapted to be attached to one portion of the screen-frame and having an arm adapted to project in inclined angular relation to the portion of the screen-frame to which such member may be attached, said projecting arm having a plurality of locking teeth extending in an elongated series therealong, and a second member for connection with another portion of the screen-frame and having a locking part for selective engagement with the teeth of said series, one of said members having an opening therein to receive a portion of the other member and said other member having a stop thereon to prevent accidental disengagement.

8. A screen-frame brace comprising a member adapted to be attached to one portion of the screen-frame and having an arm adapted to pro-

ject in inclined angular relation to the frame portion to which such member may be attached, said arm having a plurality of teeth thereon extending in an elongated series therealong, and a second member for connection with another portion of the screen-frame and having a locking part for selective engagement with the teeth of said series, one of said members having a slot therein and the other member having a stop thereon adapted to enter said slot when said members are in one position and prevent separation of said members when they are in a normal relative position.

9. A screen-frame brace comprising a member

for connection with a portion of the frame, said member being provided with a hook portion adapted to project in inclined angular relation to the portion of the frame to which such member may be connected, such hook portion having an elongated series of teeth extending therealong, a second member for connection with another portion of the frame and having an opening adapted to receive said hook portion and a locking part for selective cooperation with the teeth of said series, and a stop at the free end of said hook portion to prevent disengagement of the locking part therefrom.

GUY A. WELLMAN.
